UNITED STATES PATENT OFFICE.

ALAN ROBB FERGUSSON, OF NEW YORK, N. Y.

METHOD OF AND MEANS FOR MECHANICAL INDEXING.

1,270,934.

Specification of Letters Patent.

Patented July 2, 1918.

Application filed January 2, 1918. Serial No. 210,103.

To all whom it may concern:

Be it known that I, ALAN R. FERGUSSON, a citizen of the United States, residing at New York, in the county of New York and 5 State of New York, have invented certain new and useful Improvements in Methods of and Means for Mechanical Indexing, of which the following is the specification.

This invention relates to a method of recording and indexing and is especially applicable for making a permanent record of any name, which record accompanies the name and is upon its face the means whereby it can be located or placed in a file instantly 10 at any time thereafter. More particularly the invention consists in first translating any name into a number, according to a predetermined plan; in then recording each resulting number in a certain color upon a separate 15 sheet or card, the color also being determined by said predetermined plan, and then arranging said sheets or cards according to the value and color of the numbers thereon.

My new system is especially adapted to 20 the recording of exceedingly large lists of names, such for example as those occurring in the telephone directory of a large city, in large mail order houses, and the like, without the confusion that would result if such 25 lists were attempted to be indexed according to the ordinary methods. In my new system each name is translated into a number, according to a predetermined plan, and which translation is permanent, the number for all 30 times taking the place of the name, the number in itself and by itself conveying all the information requisite to dealers of the name and the key and guide, and to all future 35 dealers with an account on record. Also the

number shows upon its face instantly the 40 place in the file where the name will be located. Furthermore I dispense entirely with the necessity of any retranslation into letters, thereby making it possible to divide 45 the alphabet into three parts, using a triple series of numbers, assigning a different color to each series as a result of which the names will be filed both numerically and alphabetically, enormously simplifying the system 50 and making it possible to use a single digit for each letter of the alphabet.

Among the objects of my invention is to 55 so simplify the question of indexing that not only may large lists of names be quickly indexed, but the names will at the same time

be arranged alphabetically; further to classify entirely by number and color in such way as to make any name immediately accessible without necessitating any previous consultation or study of indexes or the like; 60 further to greatly increase the accuracy of filing, refiling, and recording; further to provide a system whereby every person may have a special number which will be permanently attached to and be as immutable as 65 his name, so that wherever that individual may be, the same number will follow and apply to him and he can always be identified in correspondance, by wire, etc., by this number; further to print each individual's number or name, or both, on the index card in a color to be determined from the first letter of the surname according to a predetermined 70 plan; further to locate the position of the name in the index cards to within three 75 successive letters of the alphabet by referring to the number on the card, and then locate the exact letter of the alphabet by referring to the color in which the number is printed on the index card; also to further 80 subdivide by making use of different colored tabs in the spaces under each letter of the alphabet whereby the alphabetical arrangement may be carried out to a still greater degree; further to provide a system in which 85 the numbers representing the names will be in proper sequence and at the same time the names will fall in their proper alphabetical order, thus making possible an indexing system combining sequence in both numerical 90 and alphabetical arrangement; and such further objects, advantages and capabilities as will later more fully appear.

Referring to the drawings:

Figure 1 represents a keyboard of a typewriter, said keyboard being arranged according to my present invention.

Fig. 2 is a perspective view of a printing hammer and key of a typewriter equipped for printing cards for use in my new indexing system.

Fig. 3 is a chart on which the numerical and color values of each of the letters of the alphabet can be seen at a glance.

Figs. 4 and 5 are indexing elements constructed according to my present invention.

Fig. 6 is a perspective view of an index drawer in which the indexing elements are arranged in accordance with my present invention.

Fig. 7 is a modification of the arrangement in the index drawer of Fig. 6.

This invention is an improvement over the indexing system disclosed in my Patent No. 1,234,320. In the patent just referred to the alphabet is divided into a plurality of series of numbers running from 1 to 9, the particular arrangement and relation between the letters and numbers being represented 10 therein as follows:

1	2	3	4	5	6	7	8	9	1
q	w	e	r	t	y	u	i	o	p
2	3	4	5	6	7	8	9	1	
15	a	s	d	f	g	h	j	k	l
	2	3	4	5	6	7	8	0	
	z	x	c	v	b	n	m	.	

By ascertaining this relation between the 20 letters of the alphabet and the numbers assigned thereto, which may be done by merely writing the name with its corresponding number on a typewriter equipped with the key section and hammer shown in Fig. 2, 25 any name of a large list to be indexed can be quickly transposed into its corresponding numbers, it, however, not being necessary to transpose all the letters of the name, but merely a selected number,—such for example, as the initials, and first two and last 30 two letters of the surname, or any other desired number of the letters. These numbers, as is disclosed in my said patent, are placed upon an indexing card and thus furnish 35 means for quickly finding or placing said card in its proper place in the indexing drawer.

By the relative arrangement of the letters and numbers as used in my above mentioned 40 patent, and which arrangement is set forth herein above, the numbers interpreted from the name by the typewriter and filed in sequence would place the names alphabetically in great irregularity. Also in any 45 other arrangement of letters and numbers, except as hereinafter suggested, the numbers would be in sequence, but the alphabet irregular. The following arrangement of letters and numbers, however, when the 50 numbers were in proper sequence, would bring the first letter of the name in approximate but not accurate alphabetical order.

55	A	B	C	D	E	F	G	H	I
	1	1	1	2	2	2	3	3	3
	J	K	L	M	N	O	P	Q	R
	4	4	4	5	5	5	6	6	6
	S	T	U	V	W	X	Y	Z	
60	7	7	7	8	8	8	9	9	9

However, while the above arrangement with numbers filed in perfect sequence will automatically bring the first letter of the names beginning with A—B—C before those 65 beginning with D—E—F, it will not insure

any alphabetical regularity;—for example, the name Ball (whose number according to the last proposed arrangement would be 1144) would be filed before Allen (whose number according to the last mentioned system would be 1425,—the numbers corresponding to the first two and last two letters being used.)

In order to obviate this difficulty and bring the names in the indexing system in proper alphabetical order, as well as in numerical sequence, I propose an arrangement of letters, numbers and colors automatically produced by the typewriter. This will furthermore prevent duplication of numbers. In 75 the plan of my patent referred to above the number combinations must be made up from a base of nine digits, 1 to 9,—that is, nine elements to work into combinations enough to produce all the names in the world. As 80 these nine digits are used in combination three times to provide the twenty-six letters of the alphabet with numbers, it is an obvious fact that duplication of numbers will occur representing different names. In 85 order to prevent this, we must have as many elements of numbers as there are letters in the alphabet. To accomplish this, I employ three distinct colors, preferably red, green and blue, and apply the numbers and colors 90 to the letters as indicated in Fig. 3 of the drawing, it being here pointed out that in this figure the vertical section lines represent red, the horizontal section lines representing blue, and the slanting section lines 95 representing green. This particular selection of direction of section lines to represent the various colors will be adhered to throughout this specification, and is also made use of in Figs. 1, 2, 6 and 7 in addition 100 to Fig. 3. It is thus seen that according to the present invention, the arrangement of the letters, numbers and colors is as follows:—

A	B	C	D	E	F		110
Red	Green	Blue	Red	Green	Blue		
1	1	1	2	2	2		
G	H	I	J	K	L		
Red	Green	Blue	Red	Green	Blue,		115
3	3	3	4	4	4		
etc.							

Thus it will be seen that we have as many color number elements as we have letters in the alphabet and there will be no duplication 120 of numbers except where the names are the same, which cases will be differentiated by the numbers of the initials. The only possible duplication is two names and initials identically the same, such as John 125 Smith and John Smith, in which case the addresses must be depended upon in order to differentiate between the two as in standard alphabetical files, or a distinctive mark might be assigned.

In carrying into use this arrangement of letters and numbers in combination with three colors, in order to produce twenty-six indexing elements, I make use of a specially arranged typewriter, the keyboard arrangement of which is illustrated in Fig. 1 and the printing hammer in Fig. 2, it being here pointed out that such typewriter may be arranged to print each letter and its corresponding number simultaneously or separately as desired. Referring to Fig. 1, it will be seen that the keyboard of this typewriter which I propose to use has the upper surface of each of the keys colored in order to carry out the color scheme referred to above;—for example, the key having the letter Q and its corresponding number 6 is colored green as indicated by the slanting section lines, which color is also applied to the keys having the letters W and E, as well as others, while the key having the letter R as indicated by the horizontal section lines is colored blue, and the key carrying the letter Y, as indicated by the vertical section lines, is colored red; this idea being carried out to apply appropriately to each of the keys of the typewriter. The particular relation between the letters, numbers and colors will, as pointed out above, be ascertained at a glance from the chart illustrated in Fig. 3.

This typewriter will be provided with a three color ribbon, green, blue and red, with the usual shift that enables the writing in any one of the three colors. It has been pointed out above that the name Ball would, without the colors, be filed before the name Allen; Ball's number being 1144, and Allen's number, by selecting the first two letters and the last two, 1425. Now by using the color system and the typewriter just referred to, the person operating the typewriter sees when starting to write the name Ball that the B key of the typewriter is green,—therefore, she throws the ribbon shift to green and writes the whole number 1144 in green. When she goes to write the name Allen, she sees that the A key (A being the first letter of the name) is red,—therefore, she shifts the ribbon and writes the number 1425 entirely in red. Now by noting the color arrangement of the numbers, it will at once be seen that A is red and comes before B which is green.

Attention is now called to Fig. 6, in which it will be seen that the card bearing the name Allen (red) would be filed under A—1 (red number) 1425. Also the card bearing the name Ball (green) whose number is 1144 (green number) would be filed under the section B—1 (green). It will thus be seen that there is a perfect sequence of numbers under each letter. It might be that there would be, for example, three different names each number 1632. However, each will be of a different color, and would consequently be

filed under A—1 (red), B—1 (green) and C—1 (blue). Duplications of numbers in the same file section are impossible and the names will be in alphabetical order and the groups represented by the numbers 1000, 70 2000, 3000, 4000, etc., and will be in perfect numerical sequence, thus providing a system where the name can be found without the number and by alphabetical reference and the number can be found without the 75 name.

My system may be modified as illustrated in Fig. 7 by further sub-dividing the section between A—1 and B—1, or other sections, into smaller sections, by the use of 80 suitable tabs bearing colors, such for example, as seen in Fig. 7, in which the tab bearing the color green and one bearing the color blue has been placed to sub-divide the section between A—1 and B—1. This feature of sub-dividing may be successfully carried to any further degree desired by an appropriate arrangement and location of the colors.

As pointed out above, the letters selected 90 from the name being indexed, for transposition into numbers may be the initials and the first two and last two letters of the name, or any other particular combination desired, the inventive idea still being the same regardless of the particular letters chosen for translation into numbers. Also if desired, the numbers may be grouped in such a manner that certain of them may represent file units, as for example, one or more of said 100 numbers could represent the particular filing section, another one or more the particular cabinet, another one or more the drawer, and so on.

Having now described my invention, 105 I claim:—

1. An indexing element bearing numerical digits between 1 and 9 inclusive, each letter of a selected number of the letters forming the name indexed being represented by a 110 single digit between 1 and 9 inclusive, and said numerical digits appearing on said indexing element in a given color selected according to a predetermined plan.

2. An indexing element bearing numerical digits between 1 and 9 inclusive, each letter of a selected number of the letters forming the name indexed being represented by a single digit between 1 and 9 inclusive, and said numerical digits being formed on 120 said indexing element in a certain one of a plurality of colors, the particular color used being chosen according to a predetermined plan.

3. An indexing element bearing numerical 125 digits between 1 and 9 inclusive, each letter of a selected number of the letters forming the name indexed being represented by a single digit between 1 and 9 inclusive, varying significance being assigned to numbers 130

by color variation according to a predetermined plan and all of said digits being formed on said indexing element of the particular color belonging to the first digit of 5 the number being indexed.

4. An indexing element bearing two sets of characters comprising the name being indexed and a number, said number being made up of digits between 1 and 9 inclusive, 10 each letter of a selected number of the letters of said name being represented in said number by a single digit between 1 and 9, and one of said sets of characters being printed on said card in one of a plurality of 15 colors, the particular color used being chosen according to a predetermined plan, the location of the indexing element in the index drawer being determined both by its numerical value as well as its color.

20 5. The method of indexing which consists in transforming the name being indexed into a numerical number made up of digits between 1 and 9, each of said digits representing one letter of a selected number 25 of the letters of said name, placing said name and said number on an indexing element, either the number or name, or both, being formed in a color determined by a predetermined plan from the first letter of 30 the name, and arranging a plurality of said elements according to number and color.

6. An indexing element bearing numerical digits between 1 and 9 inclusive, each letter of a selected number of the letters form-

ing the name indexed being represented by a 35 single digit between 1 and 9 inclusive, and said numerical digits appearing on said indexing element in a given color selected according to a predetermined plan, said numerical digits also being grouped to correspond to filing units. 40

7. An indexing element bearing two sets of characters, one set being a number and the other set being a name, the number being formed of digits between 1 and 9, and each 45 of the digits in said number representing one letter of a selected number of the letters forming said name, and both of said sets of characters being formed in one of a plurality of colors, the particular color used being determined by a predetermined plan, whereby 50 said name may be quickly indexed according to both numerical and alphabetical sequence.

8. An indexing element bearing numerical digits, each letter of a selected number of letters forming the name indexed being represented by a single digit, and said numerical digits appearing on said indexing element in a given color selected according to 55 a predetermined plan.

In witness whereof, I hereunto subscribe my name to this specification in the presence of two witnesses.

ALAN ROBB FERGUSSON.
